UNITED STATES PATENT OFFICE.

ALEXANDER HARRIS, OF NEWARK, NEW JERSEY, ASSIGNOR TO LOUIS V. ARONSON,
OF NEWARK, NEW JERSEY.

DESIGN FOR A SCREWDRIVER.

56,812.

Specification for Design.

Patented Dec. 28, 1920.

Application filed January 7, 1920. Serial No. 350,029. Term of patent 3½ years.

To all whom it may concern:

Be it known that I, ALEXANDER HARRIS, a citizen of the United States, residing at Newark, in the county of Essex and State of New Jersey, have invented a new, original, and ornamental Design for a Screwdriver, of which the following is a specification, reference being had to the accompanying

drawing, forming part thereof, in which—

Figure 1 is a plan view, and

Fig. 2 an edge view of a screw driver, showing my new design.

I claim:

The ornamental design for a screwdriver, as shown.

ALEXANDER HARRIS.
